UNITED STATES PATENT OFFICE.

JOHN M. ABRAMS, OF BROOKLYN, NEW YORK.

PNEUMATIC SAW.

1,306,395.

Specification of Letters Patent. Patented June 10, 1919.

Application filed September 24, 1918. Serial No. 255,521.

To all whom it may concern:

Be it known that I, JOHN M. ABRAMS, a citizen of the United States, and a resident of Brooklyn, in the county of Kings and 5 State of New York, have invented certain new and useful Improvements in Pneumatic Saws, of which the following is a specification.

The invention relates to fluid-actuated and 10 automatic tool operating devices, and more particularly to such as are designed for the operation of cutting tools, for example of the character of a saw. In devices of this character, the cutting action is effected preferably on the inward stroke of a reciprocatory member controlled by a suitable motive fluid under pressure. Such apparatus allows of rapid working of the wood and is particularly suitable for use in shipyards 15 20 where wood is used to a large extent in the construction of various types of marine craft. The ordinary type of pneumatic tool with its rapidly moving and forceful plunging piston is entirely unsuitable for this 25 30 class of work; and it is the object of the present invention to provide a device of the character aforesaid which shall be simple in construction, positive in its action, and which will afford a sufficiently powerful and uniform pull on the tool member.

A further object of the invention consists 35 in novel means for controlling the supply of fluid and the arrangement of same in relation to the ports of the device.

The nature of the invention will be best 40 understood when described in connection with the accompanying drawings, in which—

Figure 1 is a front elevation illustrating 45 the invention as embodied in an automatically operated saw.

Fig. 2 is a longitudinal section thereof.

Fig. 3 is a fragmentary longitudinal section 50 illustrating the relation of the various members at the completion of the cutting stroke.

Figs. 4 and 5 are transverse sections taken respectively on the lines 4—4 and 5—5, Figs. 1 and 3.

Similar characters of reference designate 55 corresponding parts throughout the several views.

Referring to the drawings, 10 designates a partly open casing suitably bored to provide a cylinder 11 in which is adapted to reciprocate a hollow piston member 12. The latter carries a rod which at its outward end has

secured thereto the shank 13 of the tool, for example, a saw blade 14, said rod passing through a suitable stuffing box 15 at the forward end of the cylinder and which closes 60 the latter at this end. Piston 12 is guided against rotational movement through a feather 16 of substantial proportions attached to said piston and movable with same in a guide-way or cutaway portion 17 of the 65 cylinder wall. At the opposite end, the cylinder is closed by a head 18 which carries at its extreme outer end a handle 19 and control mechanism for the admission of fluid, said handle and head for this purpose being 70 provided with the passageway 20, adapted to communicate with the interior of the cylinder, and to which external connection may be made in any suitable manner. The casing carries also at its forward end a further 75 handle 21. The foregoing features form no essential part of the invention, which relates more particularly to the manner of effecting the reciprocation of the piston 12 to provide a powerful and uniform pull on 80 the saw blade, preferably, during the inward stroke of said piston.

To this end, the passage of fluid through passageway 20 is interrupted by means of an automatic valve member 22 adapted to reciprocate, without rotary movement, at right angles to the longitudinal axis of the piston 12 in a valve chamber 23 provided in the head of casing 10. This valve is sprung-urged in one direction, across the axis of the 90 piston, and has extending therethrough a duct 24 which is adapted to afford communication, when the valve is in the position indicated in Fig. 3, between passageway 20 and the interior of the cylinder at the inward 95 end of the latter through an inlet port 25 thereof. The valve is maintained in this position under the influence of fluid under suitable pressure, as will be hereinafter more fully set forth.

In the position indicated in Fig. 2 of the drawings, the valve 22, through a further duct 26 therein, affords a relief passageway between the interior of the cylinder and an exhaust port 27 in the head of casing 10, the 105 said port 27 being also adapted to communicate with the said valve chamber 23.

In this position, a further duct 30, passing through the valve member 22, affords communication between the passageway 20 and a 110 passageway 31 extending longitudinally of the casing 10 to the forward end of the cyl-

inder and providing an inlet port 32 in the extreme forward end thereof. At the exhaust end, the valve chamber 23 is in free communication with a passageway 33 extending longitudinally of the casing 10 to the forward end of the cylinder, and terminating in a port 24 opening therein between the extreme inward and outward positions of the piston. The cylinder itself, moreover, is provided with an exhaust port 35 adapted to be uncovered when the piston reaches its extreme outward position.

The operation of the device is as follows. Assuming the members in the position as indicated in Fig. 2 of the drawings, with the piston at the extreme outward limit of its stroke, valve member 22 is in such position that its port 30 will cause the fluid under pressure to act behind the said piston, being introduced through the port 32, and effect its return movement until this source is cut off. This occurs after the piston passes the port 34, causing the fluid under high pressure to enter passageway 33 and act upon the end of valve 22 to return same in opposition to its spring to the position indicated in Fig. 3 of the drawings. Communication is thereby afforded through the passageway 20 and duct 24 to the opposite end of the cylinder to return the piston in position for its operative stroke. As soon as the piston on the return stroke passes beyond the port 34, no further fluid under high pressure is supplied to the valve chamber, and that remaining becomes exhausted through the exhaust port 27; whereupon, the spring urged valve member is returned to the position indicated in Fig. 2, and the cycle of the operations is repeated. Duct 26, being in communication with the exhaust port 27, affords a relief passageway for the exhausting of the remaining fluid

under pressure in the inner end of the cylinder.

I claim:

1. In a fluid actuated tool: the combination with the cylinder thereof and its piston, said cylinder being provided with a fluid supply port at its extreme outer end, an inlet port at its extreme inner end, an exhaust port adapted to be uncovered by the inner end of the said piston when it has reached the outward position of its stroke, and an additional exhaust port between the limits of travel of the outer end of said piston; of a valve to control the supply of fluid to said supply port and to the inlet port, and actuated in one direction of its movement by the fluid delivered through said intermediate port.

2. In a fluid actuated tool: the combination with the cylinder thereof and its piston, said cylinder being provided with a fluid supply port at its extreme outer end, an inlet port at its extreme inner end, an exhaust port adapted to be uncovered by the inner end of the said piston when it has reached the outward position of its stroke, and an additional exhaust port between the limits of travel of the outer end of said piston; of a valve to control the supply of fluid to said supply port and to the inlet port and actuated in one direction of its movement by the fluid delivered through said intermediate port, and resilient means operating to urge said valve in the opposite direction.

Signed at Brooklyn, in the county of Kings and State of New York, this 20th day of September, A. D. 1918.

JOHN M. ABRAMS.
